(57) **CLAIM**

The ornamental design for a dusting mitt, as shown and described.

DESCRIPTION

FIG. 1 is a perspective view of a first embodiment of the dusting mitt;

FIG. 2 is a front view of the first embodiment of the dusting mitt;

FIG. 3 is a side view of the first embodiment of the dusting mitt;

FIG. 4 is a bottom view of the first embodiment of the dusting mitt;

FIG. 5 is a perspective view of a second embodiment of the dusting mitt;

FIG. 6 is a front view of the second embodiment of the dusting mitt;

FIG. 7 is a side view of the second embodiment of the dusting mitt;

FIG. 8 is a bottom view of the second embodiment of the dusting mitt;

FIG. 9 is a perspective view of a third embodiment of the dusting mitt;

FIG. 10 is a front view of the third embodiment of the dusting mitt;

FIG. 11 is a side view of the third embodiment of the dusting mitt; and,

FIG. 12 is a bottom view of the third embodiment of the dusting mitt.

The rear views of the embodiments shown in FIGS. 1, 5 and 9 are identical to the front views shown in FIGS. 2, 6 and 10, respectively. Thereofre, the rear views have not been shown. In FIGS. 1 and 2, the dashed lines represent stitching, whereas in FIGS. 5 and 6, the shaded areas represent other types of bonding.
